UNITED STATES PATENT OFFICE.

FREDERIC W. HILLARD, OF BENTLEY MANOR, NEW YORK, ASSIGNOR TO MARY R. HILLARD, OF MIDDLEBURY, CONNECTICUT.

TYPE-WRITING MACHINE.

1,088,421.

Specification of Letters Patent. Patented Feb. 24, 1914.

Original application filed May 18, 1894, Serial No. 511,685. Divided and application filed October 16, 1900, Serial No. 33,264. Divided and this application filed June 22, 1910. Serial No. 563,348.

To all whom it may concern:

Be it known that I, FREDERIC W. HILLARD, of Bentley Manor, in the county of Richmond and State of New York, have invented 5 a certain new and useful Type-Writing Machine, of which the following is a specification.

My present application is a division of my pending application Serial Number 511,685 10 which was filed May 18, 1894, and of my divisional application thereof Serial Number 33,264, filed October 16, 1900, now Patent Number 1,027,843, patented on the 28th day of May, 1912, and the present application 15 is filed in response to requirement of division made by the Patent Office.

In the accompanying drawings which form a part of this specification: Figure 1. is a plan view of the machine with the 20 greater part of the carriage removed and the carriage rack partially broken away. Fig. 2 is a sectional side elevation of Fig. 1 and shows the carriage in place. Fig. 3 is a rear elevation of the machine shown in Figs. 1 25 and 2, and it shows in full lines the carriage rack which was shown partially broken away in Fig. 1.

My present application relates to the carriage structure and to novel, simple and 30 advantageous means for shifting the carriage from lower case to upper case printing position and vice versa, and the invention comprises also a novel method of connecting the carriage rack with the carriage so as to 35 permit of a relative movement of the carriage in relation to the engaging teeth of the rack, and of mechanism in the machine whereby the engaging teeth may be maintained in their carriage controlling position 40 during the said shifting movements of the carriage from printing case to printing case, and it further consists in key operated means for operating said controlling mechanism, so as to move the rack out of its carriage controlling engagement and thus to 45 release the carriage from the escapement.

Referring to the drawings, the entire carriage, including the platen frame and platen, and the truck 43^m and carriage rack 43, the 50 running gear comprising front wheel 62^a

and rear yokes 63^b 63^b, and the release key and lever 60, 61, etc., is mounted on the shift frame, which latter wholly supports said carriage. The shifting guide rails 62 and 55 63 and the rocking members on which they are mounted constitute said shift frame; the said shift frame being pivoted to the main or stationary frame by means of the pivotal supports which are shown in the drawings. The front rail is mounted on the rocker arms 60 65 and 65^a. The rocker arm 65^a has two branches at the lower extremity, one 65^b, extending toward the front, and the other 65^c extending toward the rear of the machine. To the front end of the forwardly extending 65 arm 65^b is attached spring 66, which holds the carriage normally in forward position for printing lower case characters, and to the rear end of the rearwardly extending branch 65^c is attached the connecting wire 70 67, which is fastened at its lower end to the shift key lever. The rear rail is mounted on rocker arms 63^a, 63^a at the rear of the machine. Extending between the front and rear arms are the connecting rods 68, 68. 75 When the shift key 11 is depressed the front guide rail 62 is rocked rearwardly, and the motion is transmitted to the rear guide rail 63 through the connecting rods 68, 68. The carriage is thus shifted rearwardly as a 80 whole, including the platen carriage and the truck 43^m and the upper hinged edge of the rack member 43 which is hinged on the truck, bringing the platen into position for the printing of upper case characters. Referring to the drawings, it will be seen that the front carriage guiding and supporting wheel 62^d encircles more than one-half of the front guide rail 62, and that the sliding carriage yokes 63^b, 63^b on the rear of the 85 carriage wholly encircle the rear guide rail 63. Hence it is clear that the carriage itself, through front wheel 62^d and rear yokes 63^b, 63^b, may constitute a means whereby the rear rail 63 is shifted when the front rail 62 90 is shifted. During the shifting movement of the carriage to the rear the engaging teeth of the carriage rack are restrained from rearward movement by the rack guide 95 34 and latch 35; and during the forward or 100

return movement of the carriage to lower case position the rack teeth are restrained from corresponding forward movement by said rack guide and its spring 37. Hence it is obvious that my construction is one where-in the carriage can be shifted as a whole, including the platen carriage and the truck, from lower case to upper case and vice versa, without any corresponding movement of the 10 engaging teeth of the carriage rack; and that I have accomplished such result by jointing the rack member upon the truck so as to permit of a relative movement between said truck and said rack member during the 15 shifting movements of the carriage. It will be observed that dog 30 is held normally engaged with the rack 43 and dog 31 normally disengaged by means of rocker frame spring 38, and that such engagement is in 20 no way altered by any shifting movements of the carriage. I do not wish to limit myself narrowly in this part of my invention to the precise construction shown herein, but wish to have it understood that I claim 25 broadly herein a carriage which is shifted or oscillated with its running gear, upon rails or tracks, in combination with a guide or holder for the carriage rack, arranged and adapted to maintain the engaging teeth 30 of the rack in their carriage controlling engagement during such shifting movements of the carriage. My running gear here shown comprises front carriage roller 62^a and the rear carriage yokes 63^a 63^b.

35 Near the left hand end of the rack is the arm 43^a, which extends over the guide rail 63 and is then bent downwardly until its front end lies only slightly above the top plate of the machine. Pivoted to the left 40 hand side of the platen frame is the release lever 61, which carries on its front end the release key 60 and has its rear end so placed that when the release key is depressed the rear end will engage with the rack arm 43^a 45 and rock the rack inwardly or toward the front of the machine out of engagement with dog 30. It will thus be observed that when the release key is depressed and the rack 43 thereby swung forwardly of dog 30, 50 the carriage will be free of the escapement, since both dogs 30 and 31 will then be disengaged from the rack. Hence the carriage can be moved by hand in either direction, forward or back in its line of feed, so long 55 as release key 60 is held down.

Referring to Fig. 2 of the drawings it will be observed that the rear end of the release lever 61 is so formed that it will slip under the releasing arm 43^a of the rack member 60 farther when the carriage is shifted back to upper case than when it is in lower case position, but that said rear end of the release lever is bent into a horizontal plane so that such shifting movements do not interfere with its proper relation with the rack 65

arm. When the platen frame is lifted up for inspection of the writing, however, the release lever 61 does not engage with the rack arm 43^a.

The part numbered 34 in the drawings 70 may be indifferently styled the rack guide or the rack holder, since it serves both to hold the rack and to guide it into and out of engaging position.

It will be observed that I shift the platen carriage by a parallel movement from the one printing case to the other so that the printing point is in the same plane in lower case as in upper case; also that I provide an oscillatory movement for one member 80 of the truck (here shown as the rack member) whereby the carriage may be shifted as a whole (including the platen frame and the truck) and the platen frame be moved by a parallel movement without disarranging the 85 proper engagement between the carriage and the escapement.

In Remington typewriters, of which my present machine is a modification, and in many other commercial typewriters, each 90 type bar is provided with two characters,—a lower case letter and an upper case letter,—both letters lying in the same plane and having their faces parallel with each other. There are many advantages in such 95 parallel arrangement of the type characters. But if the two type characters are parallel with each other, then the printing surface at the platen must also be in the same plane in both cases, and consequently the platen 100 frame must be moved by parallel motion from the one printing case to the other. But meantime the rack member must be held in such position that the carriage is controlled by the escapement in both cases. 105 That is to say the rack teeth must be held in their carriage controlling engagement in both positions of the carriage. I have met the requirements of the problem thus presented by providing a carriage having a 110 platen frame and a truck hinged together and a rack member hinged upon the truck; and by further providing running gear and two oscillatory supports for the carriage and means to cause said supports to rotate 115 in unison so as to maintain the surface to be written on in parallelism in both cases, and by still further providing a holder for the rack member so that during said shifting movements there will be an opening and 120 closing movement between the truck and the rack member, whereby the engaging teeth of the rack will be maintained in their carriage controlling position during the shifting movements and in both positions of the 125 carriage.

It will thus be seen of how great importance is the joint between the truck and the rack thereon in my machine, since it permits 130 of the parallel movement of the platen

frame while still reducing the shifting motion to zero at the engaging line of the rack teeth. I am not aware that any typewriter has ever heretofore been provided with a parallel motion of the platen frame from the one printing case to the other and an oscillatory reducing movement in the truck whereby the engaging teeth of the rack are maintained in their carriage controlling position during such parallel shifting movement of the platen frame, and I therefore claim such mechanism broadly herein.

It will be further observed that in my present machine the entire carriage (both the platen frame and truck and the parts thereon) is wholly mounted on the shift frame. This I also believe to be broadly new and claim it herein accordingly. That is to say, my structure herein shown comprises three elements, namely the platen frame, the rack bar and an intermediate element connected both with the platen frame and with the rack bar. Such intermediate element I have broadly termed herein the "truck," and I believe it to be broadly new to mount all three said elements on the shift frame. I also claim broadly herein the joint between the truck and the carriage rack, whereby an opening and closing movement is provided between said parts during the shifting movements of the carriage.

Attention is called to the fact that my present carriage comprises a platen frame and a truck hinged together by one joint, and a carriage rack hinged to the truck by a second joint. I believe such combination to be new and claim it herein accordingly.

It will be obvious that my invention is of wide application and I therefore do not intend to limit myself narrowly to the specific details shown in the drawings.

Having thus described my invention, what I claim and desire to secure by Letters Patent is as follows:

1. In a typewriting machine, the combination of a main frame, a shift frame pivoted to the main frame and a carriage all the parts of which are mounted on the shift frame, means for shifting the shift frame, 50 to move the carriage to two printing positions, a rack bar pivotally mounted on the carriage and partaking of the shifting movements thereof at its pivotal points, and a holder for the rack, mounted in the machine and arranged and adapted to support the toothed edge of the rack in a substantially stationary position during said shifting movements of the carriage.

2. In a typewriting machine, the combination of a main frame, a shift frame comprising two oscillatory members pivoted to the main frame to rotate in unison and a carriage all the parts of which are mounted on said shift frame, a shift key and means operated thereby to rotate one of said oscil-

latory members and means for transmitting such rotation to the other said oscillatory member, to thereby shift the carriage by parallel movement from the one printing position to the other case printing position, 70 and a rack pivotally mounted on the carriage and partaking of the shifting movements thereof at its pivotal points, and a holder for the rack, mounted in the machine and arranged and adapted to support the toothed edge of the rack in a substantially stationary position during said shifting movements of the carriage.

3. In a typewriting machine, the combination of a main frame, a shift frame comprising two oscillatory members pivoted to the main frame to rotate in unison and a carriage comprising a platen frame and a truck, both the said platen frame and truck being mounted on the shift frame, a shift key and means operated thereby to rotate one of said oscillatory members and means for transmitting such rotation to the other said oscillatory member, to thereby shift the said platen frame by a parallel movement from the one printing position to the other case printing position and so as to maintain the printing point in the same plane for printing both upper case characters and lower case characters, and also to thereby shift said truck simultaneously with the platen frame.

4. In a typewriting machine, the combination of a main frame, a carriage comprising a platen frame and a truck, and a shift frame comprising two carriage guide ways, both of which are independently pivoted to the main frame, means for mounting said truck on one of said guide ways and means for mounting the platen frame 100 on the other said guide way and for connecting it with the truck whereby the platen frame and truck are adapted to be shifted together from one printing case to the other and whereby the platen frame is movable 105 from the one said printing position to the other by a parallel movement.

5. In a typewriting machine, the combination of a carriage comprising a platen frame and a truck and a joint between the two whereby the truck can be turned relatively to the platen frame, a shift frame, means for mounting both the platen frame and the truck on the shift frame and for moving them together thereon to two printing case positions, said means including means for maintaining the platen frame when in upper case position parallel to the position it occupies when in lower case.

6. In a typewriting machine, the combination of a main frame, a shift frame which comprises two carriage guide ways, both of which are independently pivoted to the main frame, and a platen supporting carriage comprising a platen frame and a truck 130

both of which are mounted on the shift frame and shiftable therewith to upper and lower case printing positions.

7. In a typewriting machine, the combination with the main frame, a series of type bars each bearing a plurality of printing characters, and a shift frame comprising a carriage guide way pivoted on the main frame and a second guide way which is independently pivoted on the main frame, of a carriage comprising a platen frame and a truck, both said platen frame and truck being mounted on said shift frame, and a key and connections for oscillating in unison said guide ways to shift the platen frame and truck thereon from one printing position to another.

8. In a typewriting machine, the combination with the main frame, a series of type bars each bearing a plurality of printing characters, and a carriage, of a shift frame which entirely supports the carriage and comprises a carriage guide rail pivoted in the main frame and a second guide rail which is independently pivoted in the main frame, and a key and connections for oscillating in unison said guide rails to shift the carriage thereon from one printing position to another.

9. In a typewriting machine, the combination of a main frame, a carriage comprising a platen frame and a truck, and a shift frame comprising two carriage guide ways, both of which are independently pivoted to the main frame, means for mounting said truck on one of said guide ways and for mounting the platen frame on the other guide way and for connecting the platen frame, truck and the two guide ways together for movement in unison from the one printing case to the other and a key and connections whereby the platen frame and truck are adapted to be shifted together on said shift frame from one printing case to the other and whereby the platen frame is maintained when in upper case position parallel to the position it occupies when in lower case.

10. In a typewriting machine, the combination of a main frame, a carriage comprising a platen frame and a truck, and a shift frame comprising two carriage guide rails which are each independently pivoted to the main frame, means for connecting said carriage guide rails together to cause them to rotate in unison and a shift key connected to the shift frame, said platen frame and truck being both mounted on the shift frame and movable thereon to upper case and lower case printing positions.

11. In a typewriting machine, the combination with the main frame and a series of type bars each bearing an upper case character and a lower case character, of a shift frame pivoted to the main frame, a carriage

comprising a platen frame and a truck, both the platen frame and the truck being mounted on the shift frame and movable therewith to upper and lower case printing positions.

12. In a typewriting machine, the combination of a main frame, a shift frame pivoted to the main frame, a carriage all the parts of which are mounted on the shift frame, a rack member pivoted upon the carriage and a holder for the rack which is mounted on the main frame and engages the rack and serves to maintain it in its carriage controlling position in both printing positions of the carriage, and a shift key and means operated thereby to move the shift frame and carriage to two printing positions.

13. In a typewriting machine, the combination with a main frame, of a shift frame comprising two carriage guide ways each independently pivoted to the main frame, a carriage all the parts of which are mounted on the shift frame, a rack member pivoted upon the carriage and a holder for the rack arranged and adapted to hold the toothed edge of the rack in its carriage controlling position in both printing positions of the carriage, and a shift key and connections to shift the shift frame and carriage to two printing positions.

14. In a typewriting machine, the combination with a main frame, a shift frame pivoted thereon and a carriage all the parts of which are mounted on the shift frame, of a key and connections for shifting the shift frame and carriage thereon to two printing positions, and means for causing an opening and closing movement between the carriage and the rack thereon during said shifting movements, whereby to maintain the toothed edge of the rack in its carriage controlling engagement in both positions of the carriage.

15. In a typewriting machine, the combination with a main frame, a shift frame pivoted thereon and a carriage all the parts of which are mounted on the shift frame, of a platen frame and truck in the carriage which are hinged together so as to permit of a relative movement between the two, and a carriage rack which is hinged to the truck so as to permit of relative movement between the two, a shift key and connections for moving the carriage to two printing positions and a holder for the rack which is mounted on the main frame and arranged and adapted to hold the rack in its carriage controlling engagement during the shifting movements of the carriage.

16. In a typewriting machine, the combination with a main frame, and a shift frame comprising two carriage guide ways each independently pivoted on the main frame and arranged and adapted to oscillate in unison

with each other, of a carriage comprising a platen frame and a truck which are hinged together and both mounted on the shift frame, and a rack hinged to the truck and engaged by a holder on the main frame, whereby the platen frame may be moved from one printing position to the other by a parallel movement and be maintained when in upper case position parallel to the position it occupies in lower case, while said hinged joints in the carriage and on said holder permit of a reducing movement between the platen frame and toothed edge of the rack so as to enable the rack to be held in its carriage holding position in both positions of the platen frame.

17. In a typewriting machine, the combination of a main frame, a shift frame pivoted to the main frame, a carriage all the parts of which are mounted on the shift frame, a rack member hinged upon the carriage and a holder for the rack member which is mounted on the main frame and engages the rack and serves to maintain it in its carriage controlling position in both printing positions of the carriage, and a release key mounted on the carriage and operatively connected with the rack member so as to move the rack out of its carriage controlling position to release the carriage from control of the escapement.

18. In a typewriting machine, the combination with the main frame and a series of type bars each bearing an upper case character and a lower case character, of a shift frame pivoted to the main frame, a carriage comprising a platen frame and a truck, both the platen frame and the truck being mounted on the shift frame and movable therewith to upper case and lower case printing positions, and a rack member hinged to the truck and arranged and adapted to control the carriage in both said printing positions and a release key and connections on the carriage to move the rack out of its carriage controlling position in both positions of the carriage.

19. In a typewriting machine, the combination of a main frame, a platen supporting carriage, a shift frame which entirely supports the carriage and comprises two carriage guide rails, both of which are independently pivoted to the main frame and which together constitute the sole supporting means for the carriage, a rack member hinged upon the carriage and a holder for the rack member which is mounted on the main frame and which holds the rack in its carriage holding position in all positions of the carriage.

20. In a typewriting machine, the combination with the main frame, a series of type bars each bearing a plurality of printing characters, and a carriage, of a shift frame which entirely supports the carriage and

comprises a carriage guide rail pivoted in the main frame and a second guide rail which is independently pivoted in the main frame, a key and connections for oscillating in unison said guide rails to shift the carriage thereon from one printing position to another, a rack member pivotally mounted on the carriage and a holder therefor which is mounted on the main frame and which holds the rack in its carriage controlling position in both positions of the carriage.

21. In a typewriting machine, the combination of a main frame, a shift frame pivoted to the main frame, a carriage, the entire carriage being wholly supported on the shift frame, means for shifting the shift frame to move the carriage to two printing positions, a rack member hinged upon the carriage and a holder therefor which is mounted on the main frame and which holds the rack in its carriage controlling position in both positions of the carriage.

22. In a typewriting machine, the combination of a main frame, a shift frame pivoted to the main frame, a carriage all the parts of which are mounted on the shift frame, a platen frame and a hinged rack member both mounted on the carriage, a key and connections for shifting the platen frame to two printing positions and for maintaining it in the one case in parallelism with its position in the other case, and a holder for the rack member mounted on the main frame and operatively connected with the rack member at a point adjacent to the rack teeth so as to reduce the shifting movement substantially to zero at the rack teeth, to maintain the rack in its carriage holding engagement in both case printing positions of the carriage.

23. In a typewriting machine, the combination of a main frame, a carriage comprising a platen frame and a truck, a shift frame comprising two carriage guide ways, both of which are independently pivoted to the main frame, means for mounting said truck on one of said guide ways and means for mounting the platen frame on the other said guide way and for connecting it with the truck whereby the platen frame and truck are adapted to be shifted together from one printing case to the other and whereby the platen frame is movable from the one said printing position to the other by a parallel movement, a rack pivoted on the truck and a carriage release key and connections for engaging said rack and moving it out of its carriage controlling position so as to release the carriage from the escapement.

24. In a typewriting machine, the combination of a main frame, a shift frame pivoted on the main frame, a carriage comprising a platen frame, a truck, and a hinged rack member, all of which parts are mounted on the shift frame, a key and connections for

- shifting the carriage to two printing positions, connections between the shift frame and the platen frame, truck and rack member for maintaining the platen frame when in the one printing position in parallelism with the position which it occupies when in the other printing position, and a supporting holder for the rack member whereby the engaging teeth of the rack are maintained in substantially the same carriage controlling position when the platen frame is in the one said printing position as when it is in the other said printing position.
25. In a typewriting machine, the combination of a main frame, a shift frame pivoted thereto and a carriage comprising a platen frame, a truck and a rack member all of which parts are mounted on the shift frame, joints between the platen frame and truck and between the truck and rack member, to permit of relative movement between all three said parts, and a key and connections for shifting the shift frame to move the platen frame to two printing positions.
26. In a typewriting machine, the combination with the main frame, a series of type bars each bearing a plurality of printing characters, and a carriage comprising a platen frame, a truck and a rack member all joined together, of a shift frame which entirely supports the carriage and comprises a carriage guide rail pivoted on the main frame and a second guide rail which is independently pivoted on the main frame, and a key and connections for oscillating in unison said guide rails to shift the carriage thereon from one printing position to another.
27. In a typewriting machine, the combination of a main frame, a shift frame pivoted to the main frame, a carriage which comprises a platen frame, a truck and a rack member, the entire carriage being mounted on the shift frame, and means for shifting the shift frame to move the carriage to two printing positions.
28. In a typewriting machine, the combination with the main frame, of a shift frame pivoted on the main frame and a carriage comprising a platen frame, a truck and a rack member all of which parts are mounted on the shift frame, joints between the platen frame and truck and between the truck and rack member, to permit of relative movement between said parts, a shift key and connections for shifting the shift frame and carriage to two printing positions and a carriage release key for independently moving the rack member to release the carriage from the escapement.
29. In a typewriting machine, the combination of a main frame, a carriage comprising a platen frame, a truck and a rack member, a shift frame comprising two carriage guide ways, both of which are independently pivoted to the main frame, means for mount-

ing said truck and rack member on one of said guide ways and for mounting said platen frame on the other guide way and for connecting said platen frame and truck and the two said guide ways together, and a key and connections for shifting the shift frame to move the carriage to two printing positions.

30. In a typewriting machine, the combination of a main frame, a carriage comprising a platen frame, a truck and a rack member, a shift frame comprising two carriage guide ways, both of which are independently pivoted on the main frame, means for mounting said truck and rack member on one of said guide ways and means for mounting said platen frame on the other guide way and for connecting said platen frame, truck and guide ways together for movement in unison, a key and connections for shifting both of said carriage guide ways in unison to shift the carriage to two printing positions and to maintain the platen frame in parallelism in both printing positions, a joint between the platen frame and truck to permit relative movement between the two said parts and a joint between the truck and rack member to permit relative movement between said last mentioned parts and a guide or holder for the rack member arranged and adapted to maintain the engaging rack teeth in their carriage holding position in both printing positions of the carriage.

31. In a typewriting machine, the combination with the carriage propelling power and escapement and a series of type bars each bearing a plurality of printing characters, of a carriage shiftable to two printing positions and comprising a platen frame and a truck and a carriage rack, means for shifting the platen frame and for maintaining it in the one printing position in parallelism with its position in the other printing position, and a joint between the truck and the carriage rack to permit relative movement between the two parts, and a holder or guide for the rack whereby the shifting movement of the carriage is reduced substantially to zero at the line of the rack teeth.

32. In a shifting carriage in a typewriting machine, the combination of a platen frame shiftable from lower case printing position to upper case printing position by a parallel movement, a truck hinged to the platen frame and a rack member hinged to the truck, and a supporting holder for the rack member which serves to cause an opening and closing movement between the truck and rack member during the shifting movement of the carriage, so as to maintain the engaging teeth of the rack substantially stationary.

33. In a shifting carriage in a typewriting machine, the combination of a platen

frame, a truck and a rack member all hinged together, means for shifting the platen frame from one case printing position to another by a parallel movement, and 5 oscillatory means in the truck, whereby the parallel shifting movement of the platen frame is reduced to zero at the line of the rack teeth, to maintain the carriage under

control of the escapement in both printing positions of the carriage.

Signed by me in Washington, D. C., this 21st day of June, 1910.

FREDERIC W. HILLARD.
